HIGH FREQUENCY ELECTRON DISCHARGE DEVICE AND SYSTEM

Elmer D. McArthur, Schenectady, N. Y., assignee to General Electric Company, a corporation of New York

Application January 4, 1952, Serial No. 265,014

23 Claims. (Cl. 315—5.44)

This invention relates generally to the translation of electromagnetic energy and, in particular, to novel methods and devices utilizing both space charge control of current flow and velocity modulation phenomena for the generation and amplification of electromagnetic waves. 15

The progress of the electronics industry toward the use of higher and higher frequency electromagnetic waves is, of necessity, dependent upon the development of methods and devices for the translation of such electromagnetic waves. The term "translation" as employed herein includes both the generation and amplification of electromagnetic waves. Conventional electron discharge devices, or "vacuum tubes" as they are commonly identified, are limited to low frequency operation by such factors as the inductance of leads to the tube elements, the losses by radiation from the tube structure and connecting leads, etc.

One of the more successful types of high frequency electromagnetic wave tubes, described in my article in Electronics, vol. 18, pp. 98-102 (February 1945), is a special space-charge vacuum tube, usually referred to as the "disk seal" tube. This tube is an outgrowth of the well-known low frequency, cylindrical electrode vacuum tube and is chiefly identified by its planar electrode structure which enables very small interelectrode spacings. The disk-seal tube depends for its operation, as does the low frequency vacuum tube, upon space charge control of current flow to deliver an alternating current to an output circuit. Space charge control of current flow is defined as the varying or modulating of electron flow from a cathode by changing the electric field at the surface of the cathode. In the higher frequency or microwave range, however, deleterious effects, occasioned by the time required for electrons to travel between electrodes and commonly known as "transit time" effects, occur and necessitate the reduction of interelectrode spacings to preserve the space charge control current modulation characteristics of the tube. In some instances, the interelectrode spacings of the disk-seal tube are of the order of 0.1 mm. or smaller. Consequently, the disk-seal tube is limited by the mechanical difficulties inherent in maintaining the requisite close manufacturing tolerances.

The velocity modulation tube, sometimes referred to as the klystron, is another type of high frequency electromagnetic wave tube in which the comparatively long transit times encountered in the microwave frequency spectrum are utilized to advantage, rather than being minimized as in the disk-seal tube. One of the more familiar forms of the klystron comprises an electron gun which produces an accelerated beam of electrons having a constant velocity and density. This constant velocity and density beam is directed through the interaction gap of an input resonator where a high frequency excitation voltage gives each electron an additional acceleration—positive or negative—depending upon the phase and magnitude of the gap voltage during passage of the respective electrons. The beam, which now contains electrons of various

2

velocities, is directed through a "drift space" or region essentially free from external electric fields in which the variations in velocity create density modulation or electron grouping. The electron groups or "bunches" are 5 then caused to traverse the interaction gap of an output resonator to excite it into oscillation and deliver power to a load. Since the velocity modulation is applied only after direct current acceleration of the electron beam to a relatively high average velocity, the requirements for 10 electrode spacings in the input gap are much less severe than in the disk-seal tube. However, as is well known to those skilled in the art, the ideal efficiency of a two-resonator klystron is 58% and is much lower in practice where circuit and beam loading losses are present. With the so-called multi-gap klystron, the ideal efficiency may be increased to about 74%, but the additional structural complexity of the device tends to offset this advantage materially to those concerned with its manufacture and use. An 15 extensive discussion of klystron characteristics, as well as those of the disk-seal tube, may be found in the Radiation Laboratory Series, volume 7, entitled Klystrons and Microwave Triodes and authored by Donald R. Hamilton, Julian K. Knipp, and J. B. Horner Kuper (1948).

20 It is a principal object of this invention to provide new and improved methods and devices utilizing both space charge control and velocity modulation of an electron stream whereby the inherent limitations of both the disk-seal tube and the klystron are obviated.

25 In accordance with the present invention there are provided methods and devices in which an electron stream is initially modulated at the same input frequency with both space charge control and velocity components and then directed through a "drift space" or essentially electric field-free region. After its passage through the drift space wherein density modulation or "bunching" occurs as a result of the initial velocity modulation, the bunched electron stream is caused to excite an output circuit whereby power may be delivered to a load.

30 A variety of input electrode structures may be employed to obtain the initial space charge control and velocity modulation of the invention. In each case, however, enhanced efficiency is obtained by arranging the input electrode structure, in conjunction with operating conditions, to secure a predetermined phase angle between the initial current modulation component provided by space charge control and the total transit time or transit angle of the electrons from the inception of the space charge control to the end of the "drift space." The greatest enhancement of efficiency occurs when the time-varying total transit angle leads the space charge control current component in phase by 90° or when the phase angle equals $+\pi/2$, and this is true regardless of the form of 35 input electrode structure and regardless of whether the fundamental or a given harmonic of the input frequency is utilized. Further enhancement of efficiency is realized by also arranging the invention to obtain a predetermined value of a "bunching" factor which is a measure of the degree of bunching of the electron stream as it leaves the drift space. As a specific example, for 100% sinusoidal modulation of the electron current by the space charge control component, maximum efficiency for fundamental frequency occurs when the "bunching" factor equals 1.47 and the above-mentioned phase angle equals $+\pi/2$. 40 Moreover, the invention makes it possible to secure very high efficiencies at harmonic frequencies, thereby enabling the progress of the electronics industry toward the use of higher and higher frequencies.

45 40 The features of the invention desired to be protected are set forth in the appended claims. The invention itself, together with further objects and advantages there-

of, may best be understood by reference to the following specification taken in connection with the accompanying drawings in which Fig. 1 is a simplified schematic useful in explaining the invention; Figs. 2, 3, 3A, 4, 5 and 6 are graphs which are employed to illustrate the interdependence of various parameters of the invention; Fig. 7 is another simplified schematic useful in explaining a diode input structure according to the invention; Fig. 7A is a graph illustrating the efficiency of a diode input structure of the invention; Fig. 8 is a simplified section view of a diode input device according to the invention; Fig. 9 is a schematic illustration, partly in section, of feedback means which may be employed in conjunction with the devices of the invention; Fig. 10 is a simplified perspective view of another embodiment of a diode input device utilizing wave guides according to the invention; Fig. 11 is a sectionalized representation of another embodiment of the invention especially adapted for high power applications; and Fig. 12 is a section view of a further embodiment of the invention in which a triode input structure is utilized.

As has been outlined above, the disk-seal tube and the klystron or velocity modulation tube obtain their operational characteristics from contrasting physical phenomena, i. e., space charge control and velocity modulation of an electron stream. For this reason the analytical treatments of these two general microwave tube types have been mutually exclusive and basically divergent. According to the present invention, however, there are provided novel methods and devices wherein an electron stream is initially modulated at the same input frequency with both space charge control and velocity modulation and then directed through a drift space; consequently, the heretofore known analytical treatments are not applicable. The following description of the present invention, therefore, contains an analysis treating the requisite space charge control and velocity modulation components of an electron stream. As will be seen, this analysis presents a theory which enables a clear and complete description of the invention and also defines the manner in which the various parameters must be arranged to secure the many advantages of the invention.

For an understanding of the present invention, reference may be had to the simplified representation of Fig. 1 in which the numeral 1 denotes a drift space or field-free region having a length L. This representation will be employed in the ensuing analysis, along with certain assumptions, to facilitate the derivation of conditions which must be observed according to the invention.

To begin with, it will be assumed that an electron stream is generated in some fashion and directed through drift space 1 from left to right as indicated by arrow 2. It will also be assumed that the electron stream has both velocity modulation and space charge control current modulation components prior to its entrance into drift space 1. In order to maintain the consideration of these components of the electron stream in the most general form, the instantaneous output current, caused by the bunched electron stream at the time of its emergence from drift space 1, will be designated i_2 and defined by the following Fourier series:

$$i_2 = A_0 + A_1 \sin \omega t_2 + A_2 \sin 2\omega t_2 + \dots + A_n \sin (n\omega t_2) + B_1 \cos \omega t_2 + B_2 \cos 2\omega t_2 + \dots + B_n \cos (n\omega t_2) \quad (1)$$

where A_0 is the direct current component of output current, t_2 is the time of arrival of an electron at the exit end of drift space 1, and A_1, B_1, A_2, B_2, A_n and B_n are coefficients of the alternating components of the output current.

The generalized coefficients A_n and B_n are found by well known expedients to be:

$$A_n = \frac{1}{\pi} \int_0^{2\pi} i_2 \sin (n\omega t_2) d(\omega t_2) \quad (2)$$

$$B_n = \frac{1}{\pi} \int_0^{2\pi} i_2 \cos (n\omega t_2) d(\omega t_2) \quad (3)$$

It is apparent, however, that the integrations of Equations 2 and 3 cannot be performed directly because nothing is known about i_2 and t_2 . Nevertheless, other considerations permit a modification of these equations whereby the integrations may be computed.

Consider a small element of charge dq of the electron stream at any arbitrarily positioned plane x_a in the region preceding the entrance to drift space 1. This charge dq is defined as the charge which is contained in a section of the electron stream taken perpendicular to the direction of motion; the thickness of the section will be termed dx . Since the electron stream has been assumed as moving at some velocity, the moving charge dq constitutes an electric current, flowing through plane x_a , which by definition is:

$$i_a = \frac{dq}{dt_a} \quad (4)$$

where dt_a is the time required for the electrons carrying the charge to move through the distance dx at velocity u_a . In other words,

$$u_a = \frac{dx}{dt_a} \quad (5)$$

where u_a is the instantaneous velocity of the electrons while passing through plane x_a .

Consider next the same charge at a later time and, in particular, examine its status at the time t_2 that it crosses a plane x_2 at the exit end of drift space 1. To obtain generality, we will assume that the electron velocity has, for some reason, changed to another value u_2 . The time for the electrons to cross the same distance dx now has a new value dt_2 such that

$$u_2 = \frac{dx}{dt_2} \quad (6)$$

and the same amount of charge dq moving at the altered velocity u_2 defines a different value of electric current at the exit end of drift space 1, viz., by definition:

$$i_2 = \frac{dq}{dt_2} \quad (7)$$

If the quantity of electric charge is conserved, i. e., no electrons are lost or destroyed, we may consider the behavior of an amount of charge dq at the plane x_a and the subsequent behavior of the identical charge increment at the plane x_2 . Since no provision has been made for electrons moving anywhere but into and out of drift space 1, conservation of charge must exist. Hence, from Equations 4 and 7 respectively, we find

$$dq = i_a dt_a \quad (8)$$

and

$$dq = i_2 dt_2 \quad (9)$$

whereby

$$i_a dt_a = i_2 dt_2 \quad (10)$$

The above rationale may be used with reference to an earlier time increment dt_b during which the charge dq crosses an arbitrarily positioned plane x_b . Consequently, we may write:

$$i_b dt_b = i_a dt_a = i_2 dt_2 \quad (11)$$

This running equality obviously can be extended to as many planes as desired if such planes are assumed to be perpendicular to the direction of travel of the electron stream. As will be shown hereinafter, employment of this equality series in connection with Equations 2 and 3 facilitates the desired integrations.

We may now direct our attention to further specification of the electron current preceding its entrance into drift space 1. The instantaneous value of current of the electron stream will be designated i_0 at time t_0 when the electrons cross an arbitrarily positioned plane x_0 . The symbol x_0 merely identifies the arbitrarily positioned plane

and may or may not represent the distance from the plane x_0 to plane x_1 , which is located at the entrance of drift space 1. The current i_0 will be assumed to have alternating and direct current components of arbitrary magnitude and to be defined by the following expression:

$$i_0 = I_r + I_1 \sin \omega t_0 \quad (12)$$

where I_r = reference axis for the sine wave representing the A. C. component, I_1 = magnitude of alternating current component measured from I_r , and t_0 = time at which electron giving rise to i_0 cross the plane x_0 ; with the added provisions that i_0 is never negative and that whenever a negative value for i_0 is indicated by Expression 12, i_0 shall be assumed to be zero.

Expression 12 will be readily recognized as the form of the equation for the fundamental component of current flow in a diode, triode or tetrode, which arises from the impressed direct and sinusoidal voltages. As is customary in the treatment of triodes, several specific wave forms which are of particular interest may be derived. These are the well-known Classes A, B and C conditions of operation. In the Class A condition, the fundamental current wave form consists of a direct current component and a superimposed alternating current component of such amplitude that I_1 is equal to or less than I_r and linearly related thereto, whereby Expression 12 may be written:

$$i_0 = I_0 (1 + M \sin \omega t_0) \quad (13)$$

where $I_0 = I_r$ and

$$M = \frac{I_1}{I_0} \leq 1 \quad (14)$$

The parameter M is, as may be seen, the ratio of the fundamental of the space charge control component of electron current to the average current and will be referred to hereinafter as the modulation index of input current. For the Class B condition, $I_r = 0$ and from Expression 12

$$i_0 = I_1 \sin \omega t_0 \quad (15)$$

For the Class C condition, I_r is negative and from Expression 12

$$i_0 = I_1 \sin \omega t_0 - I_r \quad (16)$$

In Class A operation the current may be instantaneously zero at $\omega t_0 = 3\pi/2$ when $M = 1$. However, the current is zero nowhere else in each cycle, and the full sine wave is displayed. In Class B operation the current wave shape is one-half a sine wave from $\omega t_0 = 0$ to $\omega t_0 = \pi$ and zero from $\omega t_0 = \pi$ to $\omega t_0 = 2\pi$. In Class C operation the current is positive during an angle of less than 180° and is zero during the remainder of each cycle.

While the present invention contemplates the employment of all three conditions of operation, the remaining portion of the analysis will deal in detail only with the Class A condition of the space charge control component. For the other conditions, as those skilled in the art will realize, the analytical procedure is the same as in Class A except that the various integrals are evaluated not from 0 to 2π but only for the angular duration of the actual current flow.

One further factor must yet be specified to permit the calculation of integral Equations 2 and 3, i. e., the time t_2 at which an electron, which began its journey at time t_0 , arrives at the plane x_2 at the exit end of drift space 1. To obtain this, we shall assume that the electron velocity u_1 at the entrance to the drift space is of the very general form:

$$u_1 = u_{av} [1 + p_1 \sin (\omega t_0 + \alpha_1)] \quad (17)$$

where

u_{av} = average velocity.

p_1 = ratio of the amplitude of the sinusoidal component of velocity to the average velocity, with the provision that $0 < p_1 < 1$.

α_1 = arbitrary phase angle of the alternating velocity component measured with respect to ωt_0 .

As the development of the theory proceeds, we shall see that this assumption is completely justified.

We may now proceed to compute the time t_2 in terms of t_0 . Since the length of drift space 1 is L , the transit time therethrough of an electron having an entrance velocity given by Equation 17 is:

$$T_L = \frac{L}{u_1} = \frac{L}{u_{av} [1 + p_1 \sin (\omega t_0 + \alpha_1)]} \quad (18)$$

If $p_1 < 1$, Equation 18 may be rewritten using the first term of a binomial expansion to obtain:

$$T_L = \frac{L}{u_{av}} [1 - p_1 \sin (\omega t_0 + \alpha_1)] \quad (19)$$

$$\frac{L}{u_{av}}$$

20 may be equated to T_{av} , the average transit time through drift space 1, whereby by substitution into Equation 19, we obtain

$$T_L = T_{av} [1 - p_1 \sin (\omega t_0 + \alpha_1)] \quad (20)$$

25 The total elapsed time from plane x_0 to x_2 is

$$T_1 + T_L \quad (21)$$

where T_1 is the time spent by an electron in traveling from plane x_0 to the entrance to drift space 1; hence

$$t_2 = t_0 + T_1 + T_L \quad (22)$$

or by substitution of Equation 20

$$t_2 = t_0 + T_1 + T_{av} [1 - p_1 \sin (\omega t_0 + \alpha_1)] \quad (23)$$

35 Multiplying Equation 23 by ω gives

$$\omega t_2 = \omega t_0 + \omega T_1 + \omega T_{av} - \omega T_{av} p_1 \sin (\omega t_0 + \alpha_1) \quad (24)$$

At this juncture we must consider the transit angle ωT_1 to obtain an expression for t_2 in terms of t_0 . It is well known that a direct integration of the equations of force upon an electron in a discharge path such as we are here considering results in an algebraic expression for the transit angle ωT_1 , of an electron moving from plane x_0 to x_1 , which is nearly useless for further completely rigorous analysis. Nevertheless, this expression may, for present purposes, be changed to the following form:

$$\omega T_1 = \omega t_0 + m_1 \sin \omega t_0 + m_2 \cos \omega t_0 \quad (25)$$

where ωT_0 is the transit angle from x_0 to x_1 in the absence of an alternating velocity component, and m_1 and m_2 are coefficients of the trigonometric functions. This is an approximation which represents the true equation with an error generally not more than a few percent. Examples will appear hereinafter. Substituting Equation 25 into 24 and expanding the trigonometric term, we obtain:

$$\begin{aligned} \omega t_2 &= \omega t_0 + \omega T_0 + m_1 \sin \omega t_0 + m_2 \cos \omega t_0 \\ &\quad - p_1 \omega T_{av} \sin \omega t_0 \cos \alpha_1 - p_1 \omega T_{av} \cos \omega t_0 \sin \alpha_1 \end{aligned} \quad (25a)$$

60 Collecting the trigonometric terms

$$\omega t_2 = \omega t_0 - (p_1 \omega T_{av} \cos \alpha_1 - m_1) \sin \omega t_0 - (p_1 \omega T_{av} \sin \alpha_1 - m_2) \cos \omega t_0 + \omega T_0 + \omega T_{av} \quad (25b)$$

Equation 25b can be written as:

$$\omega t_2 = \omega t_0 + \psi - \rho \sin (\omega t_0 + \alpha) \quad (25c)$$

where

$$\psi_0 = \omega T_0 + \omega T_{av} \quad (25d)$$

$$\psi_1 = \rho \cos \alpha = p_1 \omega T_{av} \cos \alpha_1 - m_1 \quad (25e)$$

$$\psi_2 = \rho \sin \alpha = p_1 \omega T_{av} \sin \alpha_1 - m_2 \quad (25f)$$

$$\rho = \sqrt{\psi_1^2 + \psi_2^2} \quad (25g)$$

$$\tan \alpha = \frac{\psi_2}{\psi_1} \quad (25h)$$

As will be shown hereinafter, the size of the functions ψ_0 , ψ_1 and ψ_2 depend, in a practical adaptation, upon electrode dimensions and operating conditions and can be determined analytically for any chosen system of electrodes. The parameter ρ is a "bunching" factor and $\alpha + \pi = \theta$ is the phase angle between the space charge control current modulation component and the total transit angle, the full significance of which will appear later.

Sufficient information is now available to permit the computation of Equations 2 and 3. From the running equality (11), we may obtain

$$i_2 dt_2 = i_0 dt_0 \quad (26)$$

and substitute into Equation 2 to secure:

$$A_n = \frac{1}{\pi} \int_0^{2\pi} i_0 \sin(n\omega t_2) d\omega t_0 \quad (27)$$

Replacing ωt_2 by its equality from Relation 25c gives

$$A_n = \frac{1}{\pi} \int_0^{2\pi} i_0 \sin\{ (n)[\omega t_0 + \psi_0 - \rho \sin(\omega t_0 + \alpha)] \} d\omega t_0 \quad (28)$$

Substituting for i_0 from Equation 13, we obtain

$$A_n = \frac{I_0}{\pi} \int_0^{2\pi} (1 + M \sin \omega t_0) \sin\{ (n)[\omega t_0 + \psi_0 - \rho \sin(\omega t_0 + \alpha)] \} d\omega t_0 \quad (29)$$

In order to simplify, we shall define

$$\beta = \omega t_0 + \alpha \quad (30)$$

$$d(\omega t_0) = d\beta \quad (31)$$

and substitute into Equation 29 to obtain:

$$A_n = \frac{I_0}{\pi} \int_0^{2\pi} [1 + M \sin(\beta - \alpha)] \sin\{ (n)(\beta + \psi_0 - \alpha - \rho \sin \beta) \} d\beta \quad (32)$$

And by a similar process

$$B_n = \frac{I_0}{\pi} \int_0^{2\pi} [1 + M \sin(\beta - \alpha)] \cos\{ (n)(\beta + \psi_0 - \alpha - \rho \sin \beta) \} d\beta \quad (33)$$

By expansion of the terms in A_n and B_n and with the use of trigonometric relations, it may be shown that the term " $\psi_0 - \alpha$ " appearing in the sin and cos terms in Equations 32 and 33, respectively, has no effect upon the answer sought at the present, i. e., the magnitude of the n th harmonic of output current i_n . Therefore Equations 32 and 33 may be written respectively as:

$$A_n = \frac{I_0}{\pi} \int_0^{2\pi} [1 + M \sin(\beta - \alpha)] \sin\{ (n)(\beta - \rho \sin \beta) \} d\beta \quad (34)$$

$$B_n = \frac{I_0}{\pi} \int_0^{2\pi} [1 + M \sin(\beta - \alpha)] \cos\{ (n)(\beta - \rho \sin \beta) \} d\beta \quad (35)$$

Carrying out the integrations gives:

$$A_n = -2I_0 J_n(n\rho) \sin(n\alpha) + M I_0 \cos(n\alpha) \quad (36)$$

$$\cos(n\alpha) [J_{n-1}(n\rho) - J_{n+1}(n\rho)] + M I_0 \sin(n\alpha) \sin(n\alpha) [J_{n-1}(n\rho) + J_{n+1}(n\rho)]$$

$$B_n = 2I_0 J_n(n\rho) \cos(n\alpha) + M I_0 \cos(n\alpha) \sin(n\alpha) \quad (37)$$

$$[J_{n-1}(n\rho) - J_{n+1}(n\rho)] - M I_0 \sin(n\alpha) \cos(n\alpha) [J_{n-1}(n\rho) + J_{n+1}(n\rho)]$$

where the symbol J indicates the Bessel function of the first kind. The magnitude of the n th harmonic of alternating output current, C_n , is determined from the following relation:

$$C_n^2 = A_n^2 + B_n^2 \quad (38)$$

Squaring Equations 36, 37 and substituting into 38 produces, after simplification

$$C_n^2 = I_0^2 \left\{ 4J_n^2(n\rho) \left[1 + \frac{M^2}{\rho^2} \right] - 4M^2 J_{n-1}(n\rho) J_{n+1}(n\rho) \right. \\ \left. \cos^2 \alpha - \frac{8MJ_n^2(n\rho)}{\rho} \sin \alpha \right\} \quad (39)$$

As will now appear to those skilled in the art, Equation 39 represents the square of the magnitude of the n th harmonic of alternating current output from drift space 1 when an electron stream, which has been modulated with both space charge control and velocity modulation components as specified hereinbefore, is fed into the drift space. From Equation 39 we may obtain the optimum values for the several variables involved; thus we can determine the specific parameters for input electrode structures and circuits and for drift space 1, such being contemplated by the present invention and more fully disclosed hereinafter.

As will be seen, Equation 39 provides a basis for an expression of efficiency. If we define efficiency, η , in the usual sense as the ratio of input power to output power, we may state that η is the product of $C_n/2I_0$ and the ratio of peak A. C. output voltage to beam voltage. Thus, to find the value of α for maximum efficiency we compute the condition for which

$$\frac{d}{d\alpha} \left[\frac{C_n^2}{I_0^2} \right] = 0 \quad (40)$$

From (39) and (40) we have,

$$25 \quad 8M^2 J_{n-1}(n\rho) J_{n+1}(n\rho) \cos \alpha \sin \alpha - \frac{8MJ_n^2(n\rho)}{\rho} \cos \alpha = 0 \quad (41)$$

Equation 41 can be satisfied only by $\cos \alpha = 0$ or $\alpha = \pm\pi/2$, and this, it should be noted, is independent of the value of n . In Fig. 2 calculations of the variation of the ratio of fundamental output current to average current (for two values of ρ and for $M=1$) with respect to α are plotted and reveal that $\alpha = -\pi/2$, produces a maximum while $\alpha = +\pi/2$ produces a minimum. Consequently, for maximum efficiency, the angle α must equal $-\pi/2$, Substituting $\alpha = -\pi/2$ into Equation 39 gives

$$30 \quad C_n^2 = 4I_0^2 J_n^2(n\rho) \left[1 + \frac{2M}{\rho} + \frac{M^2}{\rho^2} \right] \quad (42)$$

40 or

$$30 \quad |C_n| = 2I_0 J_n(n\rho) \left[1 + \frac{M}{\rho} \right] \quad (43)$$

Alternatively, by substituting $\alpha = -\pi/2$ into Equations 36 and 37, the same answers may be obtained for A_n or B_n . Choosing n to be any even integer produces

$$A_n = 0 \quad (44)$$

$$30 \quad |B_n| = 2I_0 J_n(n\rho) \left[1 + \frac{M}{\rho} \right] \quad (45)$$

50 while choosing n to be any odd integer produces precisely the reverse. Therefore, whether n is odd or even, the resulting current amplitude of the n th harmonic is that stated by Equation 43.

55 To accentuate the physical significance of the angle α and the angle θ which we have previously defined as $\alpha + \pi$, we may refer to Equation 25c and write it in the following form:

$$55 \quad \omega t_2 - \omega t_0 = \psi_0 - \rho \sin(\omega t_0 + \alpha) \quad (45a)$$

60 From Equation 22, we see that

$$55 \quad \omega t_2 - \omega t_0 = \omega T_1 + \omega T_L$$

and hence that $\omega t_2 - \omega t_0$ equals the total transit angle ωT_2 from plane x_0 to x_1 . Therefore, Equation 45a may be expressed as

$$55 \quad \omega T_2 = \omega t_2 - \omega t_0 = \psi_0 - \rho \sin(\omega t_0 + \alpha) = \quad (45b)$$

$$\psi_0 + \rho \sin(\omega t_0 + \alpha + \pi) = \psi_0 + \sin(\omega t_0 + \theta)$$

70 Substituting $\alpha = -\pi/2$ into Equation 45b and expanding, we obtain

$$70 \quad \omega T_2 = \psi_0 + \rho \cos \omega t_0 = \psi_0 + \sin(\omega t_0 + \pi/2) \quad (45c)$$

In Fig. 3A, there is shown a plot of the alternating space charge control component of electron current i_0 versus ωt_0 and a plot of ωT_2 , the total transit angle for an arbit-

trary value of ρ , versus ωt_0 for $\alpha = -\pi/2$ and $\theta = +\pi/2$. As will be observed, the two sinusoids are displaced by 90° , the value of the angle α for maximum efficiency. Thus, for maximum efficiency, the total transit angle ωT_2 must lead the space charge control component of electron current by 90° . It also appears from Fig. 3A that, for maximum "bunching" of the electrons at the exit end of drift space 1 and hence for maximum efficiency, bunches must reinforce the space charge control component and therefore must be formed about the $\pi/2$, $5\pi/2$, $9\pi/2$, etc. positions of the i_0 curve. This means that the electrons in the quarter cycle to the left of these points must have their velocities decreased before entering drift space 1 since their starting times from $\omega t_0 = 0$ are earlier while electrons in the quarter cycle to the right of these points must have their velocities increased before entering drift space 1 since their starting times from $\omega t_0 = 0$ are later. Arranging the total transit angle ωT_2 to vary as illustrated in Fig. 3A produces a maximum effect of this nature.

To find the optimum value of $n\rho$, we compute the condition for

$$\frac{d}{d\rho} \left(\frac{C_n}{I_0} \right) = 0 \quad (46)$$

From (43) with $-\pi/2$ substituted for α we have,

$$\frac{d}{d\rho} \left(\frac{C_n}{I_0} \right) = 2 \left\{ J_n(n\rho) \left[-\frac{M}{\rho^2} \right] + \left[1 + \frac{M}{\rho} \right] \frac{n}{2} [J_{n-1}(n\rho) - J_{n+1}(n\rho)] \right\} = 0 \quad (47)$$

The largest output current is found, as far as the space charge control component amplitude is concerned, when $M=1$ and for this value of M in Equation 47, the optimum value of $n\rho$ may be obtained from

$$J_n(n\rho) (1 + n + n\rho) = n\rho (1 + \rho) J_{n-1}(n\rho) \quad (48)$$

Equation 48 can only be solved by numerical trial and error. It will yield a different optimum value of "bunching" factor ρ for each value of n , as is shown in Fig. 3 wherein ρ_m , the optimum value of ρ , is plotted against n . At the fundamental frequency, $\rho_m = 1.47$, a value which will be used hereinafter for illustrative calculations involving ρ_m .

It has been stated above that the present invention provides methods and devices for the generation and translation of electromagnetic waves in which enhanced efficiency is obtained. This fact is represented by Fig. 4 wherein efficiency of power conversion at the fundamental frequency is plotted versus ρ , the "bunching" parameter. In obtaining this graph, the ratio of peak alternating output voltage to beam voltage has been assumed to equal one, whereby $C_n/2I_0$ from Equation 43 ($\alpha = -\pi/2$) determines the efficiency as a function of ρ and M , the modulation index. A family of curves for various values of M is illustrated to fully display the interrelationships. Dotted line 3 denotes the locus of the efficiency maxima. It is to be specifically noted that with $M=1$, and $\rho=1.47$ the highest efficiency of approximately 93% is obtained. When $M=0$, however, no space charge control component of electron current is present; hence only velocity modulation or klystron action is applied to the electron stream, and the maximum efficiency is about 58%. Thus, the enhanced efficiency, obtained according to the instant invention by employing both space charge control current modulation and velocity modulation of the electron stream, is manifest. In the range of about $\rho=0.7$ to about $\rho=2.0$, for example, and for $M=1$, the efficiency always exceeds 80%.

With reference again to Fig. 2, the greater efficiency secured by utilization of the invention is further illustrated. While $\alpha = -\pi/2$ or $3\pi/2$ ($\theta = \pi/2$ or $5\pi/2$) always produces maximum efficiency regardless of the value of ρ and regardless of the value of M , greater efficiency than that obtained with velocity modulation alone is always realized when $0 > \alpha > -\pi$ and $\pi > \theta > 0$ (alternatively, when

$2\pi > \alpha > \pi$, and $3\pi > \theta > 2\pi$) $M > 0$, and $\rho > 0$. Solid line 4 (Fig. 2) shows the variation of the ratio of fundamental output current to average current with respect to α for $\rho = 1.47$, the value which results in the indicated maximum efficiency of 93% for an assumed unity ratio of peak alternating output voltage to beam voltage. Dotted line 5 (Fig. 2) shows a similar variation for $\rho = 2.0$. This means that, as long as some space charge control component of electron current is present in a lagging phase other than 180° with respect to the total transit angle variation and as long as some opportunity for velocity "bunching" is provided, the resultant efficiency exceeds 58%. The deliberate employment of velocity modulation and space charge control current modulation in a predetermined phase with respect to the total transit angle variation is therefore critical in the attainment of the advantages of the invention. In practice, since maximum efficiency is uniformly desirable, the use of $\alpha = -\pi/2$ and $\theta = +\pi/2$ in every application of the invention is most important.

In Fig. 5, the wave shape of the output current secured according to the invention is represented. Curve 6 illustrates the variation of relative beam current with respect to $\omega t_0 - \psi_0$ for $\rho = 1.47$ and $M = 1$; curve 7 represents average current. For comparison purposes, curve 8 for $M = 0$ is included. Particular attention is directed to the fact that the relative beam current reaches zero for all practical purposes at about $\omega t_0 - \psi_0 = \pm 120^\circ$ when $M = 1$ (curve 6) while it never can reach zero when $M = 0$ (curve 8). Thus "holes" or spaces are actually produced in the electron stream when space charge control in addition to velocity modulation is utilized as specified by the invention. This provides a clear interpretation of the enhanced efficiency of the invention, because it is easily recognized that greater efficiency arises as the electron stream is increasingly bunched to cause the electron current to approach or reach zero in between bunches.

An important facet of this invention is the provision of methods and devices for securing heretofore unobtainable high efficiencies at harmonic frequencies. Fig. 6 represents the variation of maximum efficiency, η_m , with respect to harmonic ratio, n . As will be observed, the maximum efficiency remains over 50% even for the 15th harmonic of the input frequency. While the foregoing discussion has dealt chiefly with the Class A condition of the space charge control component, the efficiency at the tenth harmonic for Class B operation, which is within contemplation of the invention, has been calculated to be 97%. With Class C operation, also envisaged, efficiencies are still higher. Therefore, the present invention has especial importance when harmonic frequencies are utilized.

It will now appear that, although the values of α , θ and ρ which result in maximum efficiency have been obtained from the foregoing general analysis, these factors depend upon physical parameters in a way which is different in detail for each form of electrode structure and operating conditions employed for the input to drift space 1. Therefore, α , θ and ρ must be related to specific electrode structure and operating conditions before the physical parameters can be calculated. The following analysis presents the calculation of the physical parameters for a diode input to a drift space.

Reference may now be had to the simplified illustration of Fig. 7 in which a drift space 10 is represented as having a diode input. In this figure plane 11 may be considered a cathode and plane 12 an electrode, which may be in the form of a grid, between which is defined an input interaction gap 13 having a width S . Following plane 12 is field-free drift space 10 having a length L' and being terminated by a plane 14. Plane 15 may be considered as an anode whereby planes 14 and 15 together define an output interaction gap 16. The output current which flows in gap 16 will be computed for this electrode system by following the same pattern and pro-

cedure used in the previous general derivation. Also the justification for the assumptions used in the general derivation will become evident as the calculations proceed.

Assume that a suitable circuit, such as a cavity resonator (not shown), is connected to cathode 11 and electrode 12 and that the circuit, together with a suitable power supply and high frequency signal source, provides an input gap voltage

$$V = V_0 + V_1 \sin \omega t = V_0 (1 + K \sin \omega t) \quad (49)$$

where

$$K = V_1 / V_0,$$

V_0 =beam voltage or average potential difference between 11 and 12, and

V_1 =amplitude of alternating potential difference between 11 and 12.

This voltage applied across the input gap would, at low frequency, produce a current flow

$$i_0' = 2.33 \times 10^{-6} \frac{(V_0)^{3/2}}{S^2} (1 + K \sin \omega t)^{3/2} \quad (50)$$

where i_0' =instantaneous current amplitude at plane 11.

It is well known that at microwave frequencies when the time of transit of an electron across a gap such as gap 13 is of the order of the period of the alternating voltage thereacross, the net circuital current is considerably modified as a result of the change in electrode potential which occurs while electrons emanating from the cathode are in transit. For present purposes, however, it is not necessary to know the net circuital current; all that is needed is a knowledge of what the current is at any one plane parallel to cathode plane 11. In particular, it is desirable to ascertain the instantaneous electron conduction current leaving cathode plane 11. As will appear from the following reasoning, this may be determined from Equation 50.

Even at the highest microwave frequencies, e. g., 40,000 megacycles, and for practical current densities, the electric field within input gap 13 changes instantaneously when the gap voltage changes. That is to say, any change in gap voltage is accompanied by a proportionate and simultaneous change in the electric field close to the cathode. Now consider a plane (not indicated in Fig. 7) located in space parallel to and an infinitesimal distance ΔX in the $+X$ direction away from cathode plane 11. The potential at this plane is determined by the gap voltage and the space charge distribution which is assumed to be essentially the same as it is at low frequency. This latter assumption takes into account all of the usual space charge effects but neglects the second order modification of space charge distribution which results when the electron transit time in gap 13 is comparable to the period of the alternating voltage; therefore, with this reservation the potential of the ΔX plane is that which is computed in the usual way from the well-known low frequency space charge equations. Since the electric field in gap 13 changes instantaneously, the potential of the ΔX plane must change in conformity with the gap voltage and with no time delay. The position of the ΔX plane is entirely arbitrary, and ΔX may be selected so small that the transit time of an electron from cathode plane 11 to the arbitrary plane is entirely negligible regardless of how high the frequency may be. Consequently, the electron conduction current flow through the arbitrary ΔX plane and from cathode plane 11 must be the same current which would flow if the frequency were very low. Thus, at time t' , the instantaneous conduction current leaving cathode plane 11 may be computed by Equation 50 even in the microwave spectrum.

In the absence of an alternating voltage across gap 13, the average current in amp./cm.² is

$$I_0' = \frac{2.33 \times 10^{-6}}{S^2} (V_0)^{3/2} \quad (51)$$

and, hence, from Equations 50 and 51,

$$i_0' = I_0' (1 + K \sin \omega t)^{3/2} \quad (52)$$

Expanding this expression into a binomial series gives

$$i_0' = I_0' (1 + \frac{3}{2}K \sin \omega t + \frac{3}{8}K^2 \sin^2 \omega t + \dots) \quad (53)$$

For present purposes including the determination of the fundamental component of output current which is obtained according to the invention with a device embodying principles illustrated by Fig. 7, only the first two terms of Equation 53 need be considered; neglect of the second order term can be shown to produce an effect of only 2 or 3%. These two terms give the instantaneous current i_0' leaving the cathode at time t' :

$$i_0' = I_0' (1 + M' \sin \omega t') \quad (54)$$

where $M' = \frac{3}{2}K$.

It will be observed that Equation 54 is the same as the assumed current wave form in Equation 13 and that, therefore, the assumed conditions in the general analysis are valid.

Following the pattern established in the foregoing general derivation, we express the instantaneous output current as a Fourier series of the form

$$i_2' = I_0' + A_1' \sin \omega t_2' + A_2' \sin 2\omega t_2' + \dots + A_n' \sin n \omega t_2' + B_1' \cos \omega t_2' + B_2' \cos 2\omega t_2' + \dots + B_n' \cos n \omega t_2' \quad (55)$$

Using the aforesaid running equality and Equation 55, the coefficients of the n th power terms become:

$$A_n' = \frac{1}{\pi} \int_0^2 i_0' \sin (n \omega t_2') d\omega t_0' \quad (56)$$

$$B_n' = \frac{1}{\pi} \int_0^2 i_0' \cos (n \omega t_2') d\omega t_0' \quad (57)$$

Now, with the aid of Equations 51 and 54 the current i_0' may be calculated from the dimensions of the electrodes and the applied voltages. In order to complete the integrations, however, it is necessary to compute $\omega t_2'$ in terms of $\omega t_0'$ for the particular electrode system of Fig. 7. This may be done in the ensuing manner.

Neglecting the effect of space charge, the electric field in gap 13 is

$$E = \frac{V}{S} \quad (58)$$

and substituting for V from Equation 49 gives

$$E = \frac{V_0}{S} (1 + K \sin \omega t) \quad (59)$$

or

$$E = E_0 (1 + K \sin \omega t)$$

where

$$E_0 = V_0 / S$$

The force on an electron in this field is

$$\ddot{X} = \frac{eE_0}{m} (1 + K \sin \omega t) \quad (60)$$

where e =electron charge and m =electron mass. Two integrations of Equation 57, with the added conditions that

$$\dot{X} = X = 0 \text{ when } t = t_0'$$

give

$$u = \dot{X} = \frac{eE_0}{\omega m} [\omega(t - t_0') - K \cos \omega t + K \cos \omega t_0'] \quad (61)$$

where u is the electron velocity, and

$$X = \frac{eE_0}{\omega^2 m} \left[\frac{\omega^2(t - t_0')^2}{2} + K\omega(t - t_0') \cos \omega t_0' + K \sin \omega t_0' - K \sin \omega t \right] \quad (62)$$

The time at which the electron leaves plane 11 is, as defined hereinbefore, t_1' . If t_1' is defined as the time of arrival of the electron at plane 12, the velocity with

13

which an electron arrives at plane 12 is found from Equation 61 to be

$$u_{12} = \frac{eE_0}{\omega m} [\omega(t_1' - t_0') - K \cos \omega t_1' + K \cos \omega t_0'] \quad (63)$$

At time t_1' the electron, having reached the plane 12, will have traveled the distance S between planes 11 and 12. This distance must be that specified by Equation 62 which, therefore, yields the relation

$$S = \frac{eE_0}{\omega^2 m} \left[\frac{\omega^2(t_1' - t_0')^2}{2} + K \omega(t_1' - t_0') \cos \omega t_0' + K \sin \omega t_0' - K \sin \omega t_1' \right] \quad (64)$$

Equations 63 and 64 may be simplified by defining the transit time across gap 13 of an electron which left plane 11 at time t_0' as

$$T'_1 = t_1' - t_0' \quad (65)$$

Substituting Relation 65 into Equations 63 and 64 produces

$$\frac{2\omega^2 Sm}{eE_0} = (\omega T')^2 + 2K \omega T_1' \cos \omega t_0' + 2K \sin \omega t_0' - 2K \sin \omega(T_1' + t_0') \quad (66)$$

and

$$\dot{X}_{12} = \frac{eE_0}{\omega m} [\omega T_1' - K \cos \omega(t_0' + T_1') + K \cos \omega t_0'] \quad (67)$$

The electron transit angle when there is no alternating voltage present across gap 13, i. e., the direct current transit angle $\omega T'_{av}$ may be found from Equation 66 by placing $K=0$. This gives the special value

$$(\omega T_0')^2 = \frac{2\omega^2 Sm}{eE_0} \quad (68)$$

Substituting this into Equation 66 and rearranging produces

$$(\omega T_1')^2 + 2K \omega T_1' \cos \omega t_0' + 2K \sin \omega t_0' - 2K \sin \omega(T_1' + t_0') - (\omega T_0')^2 = 0 \quad (69)$$

$$\omega T'_{av} = \frac{2\omega^2 T'_{av}^2 S}{L' \left[\omega T_0' - \frac{K}{\omega T_0'} \sin \omega t_0' + \frac{K}{\omega T_0'} \sin \omega(T_0' + t_0') - K \cos \omega(t_0' + T_0') \right]} \quad (74)$$

Equation 69 is a transcendental equation which cannot be solved directly for the instantaneous transit angle $\omega T'_1$. Therefore, resort must be had at this juncture to approximations for which the error may be estimated. This may be accomplished by observing that the argument of the last trigonometric term in Equation 69 contains both T'_1 and t_0' . It is also obvious from Equation 69 that its solution will have the form

$$\omega T'_1 = \omega T_0' + \text{trigonometric functions of } \omega T_0' \text{ and } \omega t_0'$$

If the variational part of T'_1 in the angle of the term $2K \sin \omega(T_1' + t_0')$ in Equation 69 is neglected, T'_0 may be substituted for T'_1 (in this term alone) and Equation 69 becomes

$$(\omega T_1')^2 + 2K \omega T_1' \cos \omega t_0' + 2K \sin \omega t_0' - 2K \sin \omega(t_0' + T_0') - (\omega T_0')^2 = 0 \quad (70)$$

Equation 70 is a quadratic which can be solved exactly for $\omega T'_1$ to give

$$\omega T_1' = -K \cos \omega t_0' \pm \omega T_0' \left[1 - \frac{2K}{\omega^2 T_0'^2} \sin \omega t_0' + \frac{2K}{\omega^2 T_0'^2} \sin \omega(t_0' + T_0') + \frac{K^2}{\omega^2 T_0'^2} \cos^2 \omega t_0' \right]^{1/2}$$

from which, by expansion of the radical with a binomial series and neglecting all trigonometric terms having ex-

ponents higher than one, the final solution for $\omega T'$ may be obtained:

$$\begin{aligned} \omega T_1' = \omega T_0' - K \cos \omega t_0' - \frac{K}{\omega T_0'} \sin \omega t_0' + \\ \frac{K}{\omega T_0'} \sin \omega(t_0' + T_0') \end{aligned} \quad (71)$$

It may be shown that the error resulting from the above mentioned approximation is of the order of 2% when

$$\frac{K}{\omega t_0'}$$

is not greater than 0.2.

The next necessary step in determining $\omega T'_2$ in terms of known functions is the calculation of the electron transit angle through drift space 10. This region has essentially no electric field except that due to space charge. Neglecting this, the electrons travel through the drift space with their entrance velocity expressed by Equation 67. The transit time T'_L through the drift space is, therefore,

$$T'_L = \frac{L'}{X_2}$$

and the transit angle is

$$\begin{aligned} \omega T'_{av} = \frac{\omega L'}{X_2} = \\ \frac{\omega E_0}{\omega m} = (\omega T'_1 - K \cos \omega T'_1 + \omega t_0' + K \cos \omega t_0') \end{aligned} \quad (72)$$

Equating K to 0 and substituting from Equation 68, we ascertain the average or D.-C. transit angle T'_{av} through drift space 10 to be,

$$\omega T'_{av} = \left(\frac{m}{2eE_0 S} \right)^{1/2} \omega L' \quad (73)$$

Substitution of Equation 73 and the value of $\omega T'_1$ from Equation 71 into Equation 72 produces

$$\begin{aligned} \omega T'_{av} = & \frac{S}{L'} \frac{\omega^2 T'_{av}^2}{\omega T'_0} \left[1 + \frac{K}{\omega^2 T'_0} \sin \omega t_0' - \right. \\ & \left. \frac{K}{\omega^2 T'_0} \sin \omega(t_0' + T_0') + \frac{K}{\omega T'_0} \cos \omega(t_0' + T_0') \right] \end{aligned} \quad (75)$$

The first factor can be simplified by substituting from Equations 68 and 73 to produce

$$2 \frac{S}{L'} \frac{\omega^2 T'_{av}^2}{\omega T'_0} = \frac{L'}{2S} \omega T'_0$$

whereby the instantaneous transit angle in the drift space $\omega T'_1$ becomes

$$\omega T'_{av} = \frac{L'}{2S} \left[\omega T'_0 + K \cos \omega(t_0' + T_0') + \frac{K}{\omega T'_0} \sin \omega t_0' - \frac{K}{\omega T'_0} \sin \omega(t_0' + T_0') \right] \quad (76)$$

Since we now have the instantaneous transit angle of electrons through both gap 13 and drift space 10, the total transit angle $\omega T'_2$ from plane 11 to plane 14 may be computed from the relation

$$\omega T'_2 = \omega T'_1 + \omega T'_L \quad (77)$$

15

In view of the fact that the actual angle $\omega t'_2$ at the time of arrival of an electron at plane 14 is desired for the remaining calculations, rather than the total transit angle $\omega T'_2$, the substitution of Equations 71 and 76 into Equation 77 will not be made here. The actual angle $\omega t'_2$ at the time of arrival of an electron at plane 14 is

$$\omega t'_2 = \omega t'_0 + \omega T'_2 = \omega t'_0 + \omega T'_1 + \omega T'_L \quad (78)$$

Equation 78 may be evaluated by substituting therein the values of $\omega T'_1$ and $\omega T'_L$ from Equations 71 and 76 respectively. When this is done and the terms properly arranged, the final solution is:

$$\omega t'_2 = \omega t'_0 + \psi'_0 - \psi'_1 \sin \omega t'_0 - \psi'_2 \cos \omega t'_0 \quad (79)$$

where

$$\Psi'_0 = \omega T'_0 \left[\frac{L'}{2S} + 1 \right] \quad (80)$$

$$\Psi'_1 = \frac{K}{\omega T'_0} \left[\left(\frac{L'}{2S} - 1 \right) (\cos \omega T'_0 - 1) + \omega T'_0 \frac{L'}{2S} \sin \omega T'_0 \right] \quad (81)$$

$$\Psi'_2 = \frac{K}{\omega T'_0} \left[\omega T'_0 \left(-\frac{L'}{2S} \cos \omega T'_0 \right) - \left(1 - \frac{L'}{2S} \right) \sin \omega T'_0 \right] \quad (82)$$

While this solution neglects the effect of space charge on the electric field, the relation for $\omega T'_0$ including space charge effects is well known and, as adapted to nomenclature employed here, becomes

$$\omega T'_0 = 0.316 f S (V_0)^{-1/2} \text{ radians} \quad (83)$$

where f = frequency in megacycles, S is in centimeters and V_0 is in volts. Alternatively,

$$\omega T'_0 = \frac{126}{\lambda} \left(\frac{S}{I'_0} \right)^{1/2} \quad (84)$$

where λ = wavelength in centimeters and I'_0 = current density in amp./cm. In the design of structures according to the invention, this corrected relation should be employed because much of the error occurring as a result of neglecting the effect of space charge in the derivation of Equation 79 may be removed in this manner.

It is now evident that substitution of the values of ψ'_0 , ψ'_1 and ψ'_2 from Equations 25d, 25e, and 25f respectively into Equation 25b yields a relation of the same form as Equation 79. Hence the employment of Equations 11, 54 and 79 to evaluate the integrals which define the Fourier coefficients, viz. Equations 56 and 57, yields precisely the same final relations as those determined in the foregoing general solution. We may therefore state that the output current in gap 16 is given by Equation 39 with values of ρ and α , termed ρ' and α' when referred specifically to the diode input case presently being discussed, determined from

$$\rho' = \sqrt{(\Psi'_1)^2 + (\Psi'_2)^2} \quad (85)$$

and

$$\tan \alpha' = \frac{\Psi'_2}{\Psi'_1} \quad (86)$$

along with Equations 81 and 82. Thus, the results obtained in the general solution may be specifically applied to the diode input case once the functions ψ'_0 , ψ'_1 and ψ'_2 have been derived, thereby obviating the necessity of further analysis.

It has been shown in the foregoing general solution that optimum efficiency is obtained for $\alpha' = -\pi/2$ and $\theta' = +\pi/2$. Equation 86 shows that for the diode input case this stipulation requires, when $\alpha' = -\pi/2$ and $\theta' = +\pi/2$, that

$$\psi'_1 = 0 \quad (87)$$

$$\psi'_2 \neq 0 \quad (88)$$

16

The structural and operating conditions which make

$$\alpha' = -\pi/2$$

and $\theta' = +\pi/2$ may be found, therefore, by placing Equation 81 equal to zero. This then demands a value of $\omega T'_0 = 2\pi$ for satisfaction.

Substituting $\omega T'_0 = 2\pi$ into Equation 82 gives

$$\Psi'_2 = K \left(1 - \frac{L'}{2S} \right) \quad (89)$$

and consequently both Equations 87 and 88 are satisfied. A further result of this choice of parameters is found by substituting $\psi'_1 = 0$ into Equation 85 to get

$$\rho' = \pm \Psi'_2 = \pm K \left(1 - \frac{L'}{2S} \right) \quad (90)$$

Since in a practical case, the "bunching" factor, ρ' , is always a positive number and the ratio

$$\frac{L'}{2S}$$

is greater than one, we select the proper algebraic sign from Equation 90; hence

$$\rho' = K \left(\frac{L'}{2S} - 1 \right) \quad (91)$$

is the usable form of Equation 90.

For further consideration of the diode input case as schematically illustrated in Fig. 7, it is convenient to introduce a new parameter N as follows. From Equations 68 and 73 we find

$$\frac{\omega T'_{ax}}{\omega T'_0} = \frac{L'}{2S} \quad (92)$$

Defining N as

$$N = \frac{\omega T'_{ax}}{2\pi} \quad (93)$$

and substituting Equations 92 and 93 into 91 with $\omega T'_0 = 2\pi$ gives

$$\rho' = K(N-1) \quad (94)$$

Since we know from the foregoing general analysis that maximum efficiency at fundamental frequency occurs in the diode case when $\rho' = \rho'_m = 1.47$ and $M' = 1.0$ and since we have defined $M' = \frac{3}{2}K$, we may place these values into Equation 94 to obtain the optimum value of N as

$$N_m = 3.2 \text{ cycles} \quad (95)$$

This means that with ρ' , α' and K optimized, the electrical length of drift space 10 must be 3.2 cycles of the input frequency for maximum efficiency. Fig. 7A shows the variation of efficiency with respect to N with ρ' , α' and K having their respective optimum values. At $N=3.2$ cycles, it will be noted that the maximum efficiency at fundamental frequency is about 93%—the same value as that derived in the foregoing general analysis.

As has been shown heretofore ρ'_m and hence ρ'_m for the diode case, decreases as the harmonic ratio n increases. It may be seen from Equation 94 that, with one given structure, optimum "bunching" may be obtained over a wide range of harmonic frequencies by merely altering only the magnitude of K or, practically speaking, the magnitude of the input alternating voltage. This means that the present invention enables operation over a wide range of harmonic ratios with favorable efficiencies. Furthermore, any of the harmonic ratios may be reached with the same structure operating at the same beam voltage by simply tuning the output resonator (in a manner more fully explained hereinafter) to the desired harmonic frequency and slightly lowering the magnitude of the input alternating voltage.

With the above teachings in mind sample calculations of actual dimensions of a diode input structure according to the invention may be illustrated. We have shown that

optimum performance dictates that $\omega T'_{av}=2\pi$. Substituting this into Equation 83, we obtain

$$2\pi=0.316fS(V_0)^{-1/2} \text{ radians} \quad (96)$$

where f is in megacycles, S is in centimeters and V_0 in volts. Selecting an input frequency of 1000 megacycles and a reasonable voltage of 400 volts and inserting these values into Equation 96, we have

$$S=0.398 \text{ centimeter} \quad (97)$$

We must now ascertain whether the Child-Langmuir space charge law

$$I'_0=2.33 \times 10^{-3} \frac{(V_0)^{3/2}}{S^2} \quad (98)$$

gives a reasonable current density for the above assumptions. Substituting $V_0=400$ volts and $S=0.398$ centimeter into Equation 98, we find that

$$I'_0=\frac{2.33 \times 10^{-3}(400)^{3/2}}{(0.398)^2}=117 \text{ ma./cm.}^2 \quad (99)$$

which is a practical current density to expect from a conventional oxide coated cathode. When $M'=1$ and $K=\frac{2}{3}$, we have learned that the optimum value of N occurs at 3.2 cycles. And from Equations 92 and 93 with $\omega T'_{av}=2\pi$ as hereinbefore specified for optimum efficiency, we may write

$$N=\frac{L'}{2S}=3.2 \quad (100)$$

It is well known, however, that when space charge effects are considered, the calculated transit time in a planar-electrode diode must be modified by increasing it 50% over the space charge free calculations (see Vacuum Tubes, first edition (1948), by Karl R. Spangenberg, pp. 195-198). Applying this to the present situation, Equation 100 becomes

$$N=\frac{L'}{3S}=3.2 \quad (101)$$

Replacing S by its value calculated in Equation 97 we have

$$L'=9.6S=3.82 \text{ centimeters}$$

Thus, it is clear that, knowing the frequency and beam voltage desired, the actual dimensions of a structure according to the invention may be calculated in the above manner. And it is also clear that the present invention does not require the heretofore mentioned extremely small interelectrode spacings of a disk-seal triode.

Referring now to Fig. 8, there is shown according to the invention a diode input device comprising an input resonator 20, a drift space 21, which may be defined by a conductive non-magnetic cylinder, and an output resonator 22. Input resonator 20 includes an outer conductor 23 and an inner conductor 24 between which is inserted a sliding tuning plunger 25. Tuning plunger 25, the position of which determines the resonant frequency of resonator 20, may comprise a plurality of circumferentially-spaced metallic spring fingers 26 attached to rings 27 and 28 which are separated by insulating material 29. Rods 30 may be employed as a means of adjusting tuning plunger 25 to secure a desired resonant frequency of resonator 20. Electromagnetic energy may be supplied to resonator 20 from a suitable source (not shown) by means of a coaxial line 31, illustrated as capacitively coupled.

A stream or beam of electrons may be supplied to the diode input device of the invention by an indirectly heated cathode 32 which includes a cup-shaped member 33 having a thermionically emissive coating 34 upon the inner face thereof and a suitably supported filament 35 therewithin. Heater current is supplied to filament 35 from a conventionally represented source of direct current 36.

Drift space 21, which is essentially free of electric field, comprises a conductive hollow cylindrical portion 37 which is attached at one extremity to outer conductor 23

of resonator 20 as indicated. Orifices 38 and 39 are provided in the input and output ends of portion 37, respectively, to permit the passage through drift space 21 of the electron stream emanating from cathode 32. Across orifices 38 and 39, respectively, are positioned electrodes illustrated as grids 40 and 41 formed of wires 42 suitably fastened to the end sections of portion 37 beyond the terminations (not shown) of the orifices. Inner conductor 24 of resonator 20, which is attached to cup-shaped member 33 by means of a flanged cylindrical member 43, terminates short of the input end section of portion 37 to provide a gap 44 across which the electromagnetic field from resonator 20 may extend to supply both space charge control current modulation and velocity modulation to the electron stream emanating from cathode 32. Since the device of the invention must be evacuated to permit electron flow, the flange of cylindrical member 43 is hermetically sealed to the input end section of portion 37 by means of a cylinder 45 of a material such as glass or ceramic. A solenoidal winding 37' supplied by a source of direct current 38' may be positioned as shown to generate a longitudinal magnetic field for focusing the electron stream.

Output resonator 22 comprises an outer conductor 46 and an inner conductor 47 between which is inserted a sliding tuning plunger 48. Tuning plunger 48 may be constructed in a manner similar to plunger 25 and may include metallic spring fingers 49, rings 50 and 51, and control rods 52. Inner conductor 47 of output resonator 22 terminates short of the output end section of portion 37 to provide an output gap 53 whereby the bunched electron stream emanating from drift space 21 may excite output resonator 22 into oscillation. Supported from a flanged circular ring 54 attached to inner conductor 47 is an anode member 55 upon which the electrons impinge after exciting output gap 53. Gap 53 is bridged by a cylindrical sealing member 56 of glass or ceramic to permit internal evacuation of the device as hereinbefore mentioned. Power may be extracted from output resonator 22 and supplied to a desired utilization circuit (not shown) by means of a concentric line 57, which is illustrated as capacitively coupled.

To supply desired operating potentials to the device of Fig. 8, there is provided a conventionally represented source of direct voltage 58 having a potentiometer 59 connected thereacross. Cathode 32 is maintained at an adjustably negative potential with respect to grid 40 by means of tap 60, and anode 55 is maintained at an adjustably positive potential with respect to grid 41 by means of a tap 61 which may be connected to anode 55 as shown at 62.

It will now be understood that the device of Fig. 8 provides a means of realizing the foregoing principles of the invention. By utilizing the equations developed above, maximum efficiency is assured. The length of the input gap 44 between cathode 32 and grid 40, hereinbefore identified as S in the diode analysis, may be calculated from Equation 96 for a selected input frequency and beam voltage V_0 which is here the voltage between the ground potential of grid 40 and the negative potential of cathode 32. After ascertaining whether the Child-Langmuir space charge law gives a reasonable current density to expect from cathode 32 for the assumed input frequency and beam voltage, the length of drift space 21 may be calculated from Equation 101. The length of output gap 53 and the magnitude of the anode voltage may be selected from a range of values in a manner now apparent to those skilled in the art to give a desired efficient coupling between the bunched electron stream and output resonator 22. If it is desired to operate the device of Fig. 8 as an amplifier at fundamental frequency, we have seen that K must equal approximately $\frac{2}{3}$. Hence V_1 , the amplitude of input signal voltage for maximum efficiency, is determined by definition as approximately $\frac{2}{3}$ of the magnitude of the direct voltage V_0 across input

gap 44. Both input resonator 20 and output resonator 22 are, of course, tuned to resonate at the fundamental input frequency. If it is desired to operate the identical device as a harmonic amplifier, the value of ρ'_m for greatest efficiency at the selected harmonic ratio may be determined from Fig. 3 and the concomitant value of K calculated from Equation 94 with N remaining equal to 3.2 cycles of the input frequency. Output resonator 22 is then tuned to resonance at the selected harmonic frequency by means of plunger 48.

It is within contemplation of the present invention that the devices herein disclosed may be operated as generators of electromagnetic waves as well as amplifiers. The manner in which this may be accomplished is illustrated in Fig. 9 wherein numerals employed hereinbefore are used to identify like elements. In this figure a section 63 of adjustable length is shown connected to input coaxial line 31 at one end and capacitively coupled to output coaxial line 57 at the other end. Insulators 64 and 65 may be utilized to support the inner conductor 66 within the outer conductor 67 of adjustable section 63. As will be apparent to those skilled in the art, section 63 may be arranged at the proper length to supply a desired amount of positive feedback from the output to the input of the device whereby electromagnetic oscillations are generated.

In Fig. 10, there is shown a modification of the invention particularly adaptable for operation at very high frequencies. The illustrated device comprises an input wave guide 68, a drift space 69 and an output wave guide 70. Input wave guide 68 includes a rectangular conductor 71 which is closed at its upper end and hermetically sealed at a convenient position along its length by means of a dielectric member 72. A tuning plunger 73 having an operating rod 74 extending through a hermetically sealed flexible bellows 75 is located in the upper end of wave guide 68. A plurality of flexible spring fingers 76 provide sliding contact between tuning plunger 73 and conductor 71 of wave guide 68.

A stream of electrons may be supplied to the device of Fig. 10 by an indirectly heated cathode 77 which includes a flanged, cup-shaped member 78 having a thermionically emissive coating 79 upon the inner face thereof and a suitably supported filament 80 therewithin. Cathode 77 is insulated from conductor 71 for direct current and bypassed thereto for high frequency current by means of dielectric spacer members 81. Heating current is supplied to filament 80 from a conventionally represented source of direct current 82 connected to conductive rods 83 which are hermetically sealed to wave guide 68 by means of a dielectric spacer 84 and a box like member 85.

Drift space 69 comprises a generally rectangular portion 86 having an open end 87 which extends into input wave guide 68 and another open end 88 which extends into output wave guide 70. Across open ends 87 and 88, respectively, are positioned electrodes illustrated as grids 89 and 90 which are formed of wires 91 suitably fastened to the sides of rectangular portion 86. A solenoidal winding 92 supplied by a source of direct current (not shown) may be positioned as indicated about drift space 69 to generate a longitudinal magnetic field for focusing the electron stream which emanates from cathode 77.

Output wave guide 70 is similar to input wave guide 68 and comprises a conductive rectangular member 93 having a tuning plunger 94 hermetically sealed into the upper end thereof. At a convenient position along its length, output wave guide 70 may be sealed from the atmosphere by a dielectric spacer element 95. An anode 96 is positioned with its inner end adjacent grid 90 as shown and is supported in hermetically sealed relationship within the device by means of a rectangular dielectric section 97 and a flanged plate member 98. Anode 96 is insulated from wave guide 70 for direct current and

by-passed thereto for high frequency current by means of dielectric spacer members 99.

The operation of the device of Fig. 10 is similar to that of the device of Fig. 8, and hence will not be discussed in detail. The principles dictating prescribed operation have been set forth hereinbefore and may readily be applied by those skilled in the art. Operating voltages may be supplied to the device of Fig. 10 by means of a conventionally represented source of direct current 100, 10 connected as shown.

In Fig. 11 there is illustrated another modification of the invention which is particularly adaptable to operation at high power levels. This modification comprises an input resonator 101, a drift space 102, and output resonators 103 and 104. Input resonator 101 is defined by an outer casing 105, an inner cylindrical member 106, a cathode 107 and a cylindrical member 108 having an inverted, somewhat T-shaped, cross section. Input power may be supplied to resonator 101 by means of a capacitively-coupled, hermetically sealed, concentric line 109. Cathode 107 comprises a pair of opposed generally circular plates 110 and 111 having a plurality of circumferentially-spaced, thermionically emissive strips 112 attached therebetween. Heater power may be supplied to 20 cathode 107 from a conventionally represented source of direct current 113 through a rigid conductor 114 secured to plate 111. At the inner terminus of drift space 102, an electrode illustrated as a grid 115 formed of a plurality of circumferentially spaced wires 116, is positioned. At 25 their respective ends wires 116 are attached to conductive cylinders 117 and 118, the former of which is capacitively by-passed to a boss 119 of casing 105 by a dielectric cylinder 120. Conductive cylinder 118 is capacitively by-passed to a boss 121 of casing 105 by a dielectric cylinder 122 and is also capacitively by-passed to cylindrical member 108 by a dielectric cylinder 123. Drift space 102 extends radially from the inner ends of 30 bosses 119 and 121 to output gaps 124 and 125 in output resonators 103 and 104, respectively. Power may be 35 extracted from output resonators 103 and 104, which are coupled together through their electromagnetic fields, by means of a magnetically coupled, hermetically sealed coaxial line 126. To increase the power range of the 40 device, a suitable coolant may be circulated through a 45 cylindrical space 127 in casing 105.

In operation the device of Fig. 11 has similar characteristics to the devices of Figs. 8 and 10 with the exception that electrode 115 provides a triode input to drift space 102 for a purpose which will be more fully explained later in connection with the device of Fig. 12. Electrons emanating from cathode 107 are affected by the electromagnetic field within input resonator 101 and are given both space charge control and velocity modulation components in the gap between cathode 107 and grid 115. After the bunched electrons cross gaps 124 and 125 to excite output resonators 103 and 104, they are discharged upon an anode portion 128 of casing 105. Operating potentials may be supplied to the device of Fig. 11 from a conventionally represented source of direct voltage 129, the positive terminal of which is maintained at the same potential as casing 105. Cathode 107 is maintained at an adjustably negative potential with respect to anode 28 by means of a conductor 129', while grid 115 is held at an adjustably negative potential with respect to cathode 107 by means of a conductor 130 which is hermetically introduced into the device as illustrated.

In certain instances, it may be desirable to have some flexibility with regard to the selection of beam voltage 70 for the device of the invention. From the foregoing discussion in connection with Fig. 8, it will be observed that one particular value of beam voltage V_0 is assumed, along with the desired frequency of operation, and the remainder of the parameters for the device then calculated from the derived equations. In the device illus-

trated in Fig. 12, wherein numerals utilized hereinbefore are employed to identify like elements, there is provided a triode input to drift space 21 for the purpose of obtaining maximum efficiency over a wide range of values for the beam voltage. The device of Fig. 12 comprises an electrode shown in the form of a grid 135 inserted between cathode 32 and electrode 40. Grid 135 is formed of transversely extending wires 136 attached to a flanged conductive washer 137 which extends through dielectric cylinder 45. Washer 137 is conductively connected to a washer 138 through spring fingers 139, and washer 138 is by-passed to input resonator 20 and drift space 21 by means of dielectric washers 140 and 141, respectively. It will now be observed that by maintaining grid 135 at an adjustably negative potential with respect to cathode 32 by means of a tap 142, various values of beam voltage may be selected in conjunction with the voltage of grid 135 to achieve maximum efficiency in accordance with the foregoing principles of the invention. With the insertion of grid 135, the average transit time of electrons across the input gap becomes a function of both the voltage of grid 135 and the beam voltage. Hence, a great number of combinations of these voltages is available without the sacrifice of efficiency. Specific attention is directed to the fact that the electromagnetic fields from resonator 20 are applied between cathode 32 and grid 135 to obtain the desired space charge control and velocity modulation in the embodiment of Fig. 12.

Obviously, the feedback means illustrated in Fig. 9 or means equivalent thereto may be employed with all the various embodiments of the invention to obtain a high frequency oscillator. Furthermore, the output waves transducing means in the various embodiments of the invention, i. e., the resonators and wave guides, may be tuned to a harmonic of the frequency to which the input wave transducing means is tuned to obtain a high efficiency harmonic amplifier. Also, in the embodiments of Figs. 11 and 12, low frequency modulation voltages may be applied respectively to electrodes 115 and 135 in well known ways to insert intelligence signals into the devices.

From the foregoing it is manifest that the present invention provides methods and devices in which the translation of electromagnetic energy is accomplished in novel manner with very high efficiency. The application of both space charge control and velocity modulation components to an electron stream according to the invention may be accomplished with a variety of input electrode structures. Selection of a desired input electrode structure enables determination of the various parameters by means of the equations developed herein. As an example, detailed calculations for a diode input structure have been included in the above description. Thus, by utilization of the instant invention, new and improved methods of and devices for the generation and amplification of electromagnetic waves are realized.

While the present invention has been described by reference to particular embodiments thereof, alternative constructions will readily occur to those skilled in the art. It is therefore intended, in the appended claims, to cover all such equivalent embodiments as may be within the true spirit and scope of the foregoing description.

What I claim as new and desire to secure by Letters Patent of the United States is:

1. An electron discharge device system of the type employing an electron beam comprising a cathode for generating a beam of electrons, means providing a drift space spaced along said beam from said cathode to provide an input gap, electromagnetic wave transducing means coupled to said electron beam in said input gap to supply high frequency fields for modulating said electron beam with a space charge control component, electromagnetic wave transducing means coupled to said electron beam in said input gap to supply high frequency fields for modu-

lating said electron beam with a velocity modulation component, the total transit angle of electrons from said cathode to the exit end of said drift space having a phase angle of about $+\pi/2$ with respect to said space charge component, an anode spaced from said exit end of said drift space, and output electromagnetic wave transducing means coupled with said electron beam in the space between the exit end of said drift space and said anode for deriving electromagnetic energy from said electron beam.

2. An electron discharge device system of the type employing an electron beam comprising a cathode for generating a beam of electrons, means providing a drift space spaced along said beam from said cathode to provide an input gap, electromagnetic wave transducing means coupled to said electron beam in said input gap to supply high frequency fields for modulating said electron beam with a space charge control component, electromagnetic wave transducing means coupled to said electron beam in said input gap to supply high frequency fields for modulating said electron beam with a velocity modulation component, the total transit angle of electrons from said cathode to said exit end of said drift space having a phase angle of approximately $+\pi/2$ with respect to said space charge component, said electron beam emerging from said drift space representing an alternating current having a magnitude C_n determined by the relation

$$C_n = 2I_0 J_n(n\rho) \left[1 + \frac{M}{\rho} \right]$$

30 where I_0 is the direct current represented by the electron beam, J_n is a Bessel function of the first kind, n is any integer, ρ is a bunching parameter dependent upon the magnitude of the velocity modulation component and the length of said drift space, and M is a modulation index of the space charge control component, an anode spaced from said exit end of said drift space, and output electromagnetic wave transducing means coupled with said electron beam in the space between the exit end of said drift space and said anode for deriving electromagnetic energy from said electron beam.

3. A system as in claim 2 in which said bunching factor ρ has a value of about 1.47.

4. A system as in claim 2 in which said modulation index M has a value of about 1.

45 5. A system as in claim 2 in which said bunching parameter ρ is selected from the range of about 0.7 to 2.0 and said modulation index M has a value of about 1.

6. An electron discharge device system of the type employing an electron beam comprising a cathode for generating a beam of electrons, means providing a drift space spaced along said beam from said cathode to provide an input gap, said means including a hollow conductive member maintained at a positive potential with respect to said cathode for accelerating said electron beam in said input gap, a cavity resonator connected for high frequency currents between said cathode and said hollow conductive member to supply high frequency fields across said gap for modulating said electron beam with both space charge control and velocity modulation components, said gap

55 having a length equal to an average transit angle of the electrons in the beam 2, an anode spaced from the end of said drift space remote from said cathode, and a cavity resonator coupled with said electron beam in the space between said end of said drift space and said anode for deriving electromagnetic energy from said electron beam.

7. A system as in claim 6 in which $\rho' = K(N-1)$ where ρ' is a bunching factor, K is the ratio of potential difference between said hollow conductive member and said cathode and the amplitude of the alternating potential difference supplied by said first recited cavity resonator, and N is the length of said drift space.

8. A system as in claim 7 in which ρ' is approximately 1.47.

9. A system as in claim 7 in which ρ' is approximately

1.47, and N is approximately 3.2 cycles of the high frequency fields supplied by said first recited cavity resonator.

10. An electron discharge device system of the type employing an electron beam comprising a cathode for generating a beam of electrons, means providing a drift space spaced along said beam from said cathode to provide an input gap, said means including a hollow conductive member maintained at a positive potential with respect to said cathode for accelerating said electron beam in said input gap, a wave guide connected for high frequency currents between said cathode and said hollow conductive member to supply high frequency fields for modulating said electron beam with both space charge control and velocity modulation components, said input gap having an electrical length of 2π at the operating frequency for the positive potential applied to said hollow conductive member an anode spaced from the end of said drift space remote from said cathode, and a wave guide coupled with said electron beam in the space between said end of said drift space and said anode for deriving electromagnetic energy from said electron beam.

11. An electron discharge device system of the type employing an electron beam comprising a cathode for generating a beam of electrons, means providing a drift space spaced along said beam from said cathode to provide an input gap, said means including a hollow conductive member maintained at a positive potential with respect to said cathode for accelerating said electron beam in said input gap, a wave guide connected for high frequency currents between said cathode and said hollow conductive member to supply high frequency fields for modulating said electron beam with both space charge control and velocity modulation components, said input gap having an electrical length of 2π at the operating frequency for the positive potential applied to said hollow conductive member an anode spaced from the end of said drift space remote from said cathode, a wave guide coupled with said electron beam in the space between said end of said drift space and said anode for deriving electromagnetic energy from said electron beam, and feedback means intercoupling said wave guides for sustaining oscillations in said device.

12. A device system as in claim 10 in which said first recited wave guide is tuned to a predetermined input frequency and said second recited device is tuned to a harmonic of said predetermined input frequency.

13. An electron discharge device system of the type employing an electron beam comprising a cathode for generating a beam of electrons, means providing a drift space the entrance end of which is spaced along said beam a predetermined distance from said cathode, an electron permeable electrode positioned traversing said beam between said cathode and said entrance end of said drift space, electromagnetic wave transducing means connected for high frequency currents between said cathode and said electron permeable electrode to supply high frequency fields for modulating said electron beam with both space charge control and velocity modulation components, the total transit angle of electrons from said cathode to the entrance end of said drift space having a phase angle of about

$$+\frac{\pi}{2}$$

with respect to said space charge component, an anode spaced from the exit end of said drift space, and electromagnetic wave transducing means coupled with said electron beam in the space between said exit end of said drift space and said anode for deriving electromagnetic energy from said electron beam.

14. An electron discharge device system of the type employing an electron beam comprising a cathode for generating a beam of electrons, means providing a drift space the entrance end of which is spaced along said beam a predetermined distance from said cathode, said means

including a hollow conductive member maintained at a positive potential with respect to said cathode for accelerating said electron beam, an electron permeable electrode positioned traversing said electron beam between said cathode and said entrance end of said drift space, electromagnetic wave transducing means connected for high frequency currents between said cathode and said electron permeable electrode to supply high frequency fields for modulating said electron beam with both space charge control and velocity modulation components, the total transit angle of electrons from said cathode to the entrance end of said drift space having a phase angle of about

$$+\frac{\pi}{2}$$

with respect to said space charge component, an anode spaced from the exit end of said drift space, and electromagnetic wave transducing means coupled with said electron beam in the space between said exit end of said drift space and said anode for deriving electromagnetic energy from said electron beam.

15. A device system as in claim 14 in which each of said electromagnetic wave transducing means comprises a cavity resonator.

16. A device system as in claim 14 in which said electron permeable electrode is maintained at a negative potential with respect to said cathode.

17. A device system as in claim 14 in which said first recited electromagnetic wave transducing means is tuned to a predetermined input frequency and said second recited electromagnetic wave transducing means is tuned to a harmonic of said input frequency.

18. An electron discharge device system of the type employing an electron beam comprising a cathode for generating a beam of electrons, means providing a drift space the entrance end of which is spaced along said beam a predetermined distance from said cathode, said means including a hollow conductive member maintained at a positive potential with respect to said cathode for accelerating said electron beam, an electron permeable electrode positioned traversing said electron beam between said cathode and said entrance end of said drift space, electromagnetic wave transducing means connected for high frequency currents between said cathode and said electron permeable electrode to supply high frequency fields for modulating said electron beam with both space charge control and velocity modulation components, the total transit angle of electrons from said cathode to the entrance end of said drift space having a phase angle of about

$$+\frac{\pi}{2}$$

with respect to said space charge component, an anode spaced from the exit end of said drift space, electromagnetic wave transducing means coupled with said electron beam in the space between said exit end of said drift space and said anode for deriving electromagnetic energy from said electron beam, and feedback means intercoupling said electromagnetic wave transducing means for sustaining oscillations in said device.

19. An electron discharge device system of the type employing an electron beam comprising a cylindrical cavity resonator having a peripheral opening in the defining wall thereof, a cathode positioned within said resonator opposite said opening for generating a beam of electrons which passes through said opening, means providing a drift space for said electron beam having said opening as an entrance end, and an annular cavity resonator coupled with said electron beam at the exit end of said drift space the total transit angle of electrons from said

25

cathode to the entrance end of said drift space having a phase angle of about

$$+\frac{\pi}{2}$$

with respect to said space charge component.

20. An electron discharge device system of the type employing an electron beam comprising a cylindrical cavity resonator having a peripheral opening in the defining wall thereof, a cylindrical cathode positioned within said resonator opposite said opening for generating a beam of electrons which passes through said opening, an electron permeable grid positioned traversing said beam of electrons between said cathode and said opening such that electromagnetic waves sustained within said cavity resonator modulate said electron beam with both space charge control and velocity modulation in the space between said cathode and said grid, means providing a drift space for said electron beam having said opening as an entrance end, an annular cavity resonator coupled with said electron beam at the exit end of said drift space to extract electromagnetic energy from said beam the total transit angle of electrons from said cathode to the entrance end of said drift space having a phase angle of about

$$+\frac{\pi}{2}$$

with respect to said space charge component.

21. A device system in claim 20 in which said defining wall of said cavity resonator is maintained at a positive potential with respect to said cathode and said electron

26

permeable grid is maintained at a negative potential with respect to said cathode.

22. A device system as in claim 21 in which said electron permeable grid is by-passed for high frequency currents to said defining wall of said cavity resonator.
- 5 23. An electron discharge device system of the type employing an electron beam comprising a cathode and generating a beam of electrons, means spaced from said cathode and providing a drift space spaced along said beam from said cathode to provide an input gap, electromagnetic wave transducing means coupled to said electron beam to supply high frequency fields across said input gap for modulating said beam with a space charge control component and a velocity modulation component, the physical length of said gap corresponding to an average transit angle of electrons across said gap of 2π , an anode spaced from the exit end of said drift space, and output electromagnetic wave transducing means coupled with said electron beam in the space between the 10 exit end of said drift space and said anode for deriving electromagnetic energy from said electron beam.
